UNITED STATES PATENT OFFICE.

OLAF A. TOFFTEEN, OF CHICAGO, ILLINOIS.

OXYGENATOR AND SMOKE ELIMINATOR.

Application filed April 2, 1925. Serial No. 20,048.

This invention relates more particularly to improvements in an oxygenator of a type adapted for use in boilers, furnaces and heating plants generally.

5 The improved oxygenator is adapted to be removably placed in position on a fire grate without necessitating any changes in the construction of the boiler or furnace and furthermore adapted to pre-heat the 10 entering air and augment the quantity of oxygen to the burning fuel to cause a substantially complete combustion of the fuel, thereby obviating smoke.

It is an object of this invention to provide 15 a removable oxygenator for a boiler or furnace, said oxygenator being constructed of materials adapted to withstand the great heat to which it is necessary to subject the same.

20 It is also an object of this invention to provide an improved oxygenator adapted to pre-heat the air entering the fire chamber to cause a substantially complete combustion of the fuel and a consequent reduction of the 25 escaping volatile matter, thus obviating the production of smoke.

It is a further object of this invention to provide a fuel saving device for furnaces and the like, said device being constructed 30 of metal and carborundum products with the various parts assembled to afford a removable oxygenizer adapted when properly positioned within a fire box to cause burning of the fuel in the fire box from above 35 as well as from below so that a practically complete combustion of the fuel takes place, thereby eliminating smoke.

40 It is an important object of this invention to provide an oxygenator and smoke eliminator constructed of apertured end members which are separated by means of an intermediate member constructed of a carborundum product adapted to be heated to a very high temperature to permit white 45 heat to be produced, said material adapted particularly to withstand deterioration due to the excessive heat to which the material is subjected.

50 It is another important object of this invention to provide an oxygenator adapted for use in the fire boxes of furnaces and the like, said oxygenator adapted to pre-heat air admitted to the fire box above the bed of fuel, said pre-heated air being heated to a white heat due to the fact that the oxygenator is provided with an intermediate

member constructed of "carbofrax", a carborundum product adapted to be heated to high temperatures and furthermore adapted to retain the heat without causing deterioration of the material. 60

It is another important object of this invention to provide an oxygenator and smoke eliminator of simplified construction, constructed of selected materials such as a 65 mechanically, chemically or electro-chemically fused silicon carbide and adapted to be removably inserted as a unit in a fire box of a boiler or the like to cause practically a complete combustion of the fuel due to the 70 fact that the fuel fed burns not only from beneath, but also from above, due to the pre-heated air produced by the oxygenator.

Other and further important objects of this invention will be apparent from the 75 disclosures in the specification and the accompanying drawings.

This invention (in a preferred form) is illustrated in the drawings and hereinafter more fully described. 80

On the drawings:

Figure 1 is a longitudinal vertical section through a boiler and illustrating an improved oxygenator and smoke eliminator removably placed in position upon the grate 85 within the fire box.

Figure 2 is an enlarged vertical section of the device showing parts in elevation.

Figure 3 is a top plan view of the base member of the device. 90

Figure 4 is a transverse section taken on line 4-4 of Figure 2.

Figure 5 is a top plan view of the cap or top member of the device.

Figure 6 is a fragmentary vertical section 95 of the upper portion of a modified form of the device.

As shown on the drawings:

The reference numeral 1 indicates a boiler or heating plant having a fire box 2 within 100 which an apertured grate 3 is mounted in the regular way.

The improved oxygenator and smoke eliminator is portable and is adapted to be removably placed in any desired position 105 upon the grate 3 after which a bed of fuel is adapted to be placed upon the grate to surround the base and body portion of the device. The improved device is a combustion intensifier and comprises a base member having a shape substantially that of a wheel and consisting of a rim portion 4, a 110

centrally apertured hub section 5 and radial spokes 6 connecting the rim portion with the hub portion. The rim portion 4 is provided on its upper surface with a circular 5 groove 7. The wheel arrangement of the base affords a plurality of base apertures or 10 openings 8; the base may be formed of cast metal or other suitable material which will withstand the excessive heat to which the 15 device is subjected. Removably mounted above the base with the lower end seated in the base groove 7 is a hollow body section or intermediate housing 9 having a frustum shape. The housing 9 is constructed of a 20 particular material such as a mechanically, chemically or electro-chemically fused silicon carbide which is a carborundum product known as "carbofrax", said material adapted to be heated to approximately 4250° C. without 25 causing any signs of deterioration of the material. The "carbofrax" material of which the housing 9 is formed is not affected by heat in a way to cause combustion of the material. The "carbofrax" housing is 30 adapted to be quickly heated and has the important property of retaining heat for three or four hours after the device is removed from a fire box in which it has been heated. The housing 9 as illustrated in 35 Figure 4 is constructed of a plurality of sections 10, one longitudinal edge of which is provided with a groove while the other longitudinal edge is provided with a rib or tongue 11 to fit into the groove of an adjacent section. This construction of the housing 9 permits expansion and contraction of the end sections of the device when said end sections are constructed of metal.

Mounted upon the top of the tapered 40 housing 9 is a cap or top member 11 of a substantially double dome shape with the lower portion provided with a groove adapted to receive the upper end of the housing 9 as illustrated in Figure 2. The 45 top section 11 is provided with a plurality of radiating passages or apertures 12 and with a central aperture 13 as illustrated in Figure 5. Integrally formed within the top section 11 is a sleeve 14 which projects 50 downwardly into the housing 9. The upper portion of the sleeve 14 is provided with a plurality of apertures 15. The top section 11-14 is constructed of metal or other suitable material adapted to withstand the heat 55 to which the device is subjected.

The housing sections 10 interfit with one other and are held clamped in position between the base 4 and the top 11 by means of a tie bolt 16 which projects through the top opening 13 and through the opening in the hub portion 5 of the base. Nuts are used for the purpose of holding the base and top 60 sections clamped against the ends of the housing sections 10. A ring or eye 17 is integrally formed on the upper end of the

connecting bolt 16 for the purpose of permitting easy handling of the device.

Figure 6 illustrates a modified form of the device wherein the housing 9 is also constructed of "carbofrax" a fused silicon carbide. In this case, however, a top member or cap 18 is provided having a plurality of outlet apertures 19 therein. The top piece is constructed of carborundum or "carbofrax" or some similar material and is held 70 in place upon the upper end of the housing 9 by means of the retaining bolt 16 or other suitable means. If desired the base of the device may be constructed either of metal or carborundum or some form of carborundum 75 product similar to "carbofrax".

The improved oxygenator and smoke eliminator of this invention is adapted to be removably disposed upon the boiler grate 3 of the fire box as illustrated in Figure 1 80 after which a bed of fuel may be deposited upon the boiler grate 3 around the housing 9 and below the cap member 11. When the bed of fuel is burning the draft from the ash pit passes upwardly through the apertures in the grate tending to cause the bed of fuel to burn from beneath. Part of the draft passing through the grate enters the device through the base apertures 8 and then passes upwardly through the housing 9 which being constructed of "carbofrax" 85 readily absorbs and retains a maximum quantity of heat. The air thus passing upwardly through the housing 9, becomes superheated and passes upwardly through 90 and around the sleeve 14 and out of the cap discharge openings 12. The cap discharge openings 12 are so positioned that the superheated air jets discharged therethrough reach practically all parts of the upper portion 95 of the fire box 2. It will thus be noted that superheated air is discharged above the bed of fuel on the grate thereby causing the bed of fuel to burn from above as well as from below. The air passing upwardly 100 through the oxygenator becomes superheated producing white heat which is discharged in blasts or flames through the top openings 110 into the combustion chamber of the boiler fire box. The degree of heat produced is 110 so intense that the oxygen in the air is superheated and liberated, thereby permitting the same to readily unite with the fuel gases and the volatile carbon products emitted from the upper portion of the fuel 120 bed, thus tending to cause a substantially complete combustion of the fuel. The intensely superheated air entering the fire box above the fuel bed serves to cause a substantially complete combustion as hereinbefore stated with the result that the products usually forming smoke are reduced to a minimum, thus eliminating the discharge of smoke through the flue pipes of 125 the boiler.

The "carbofrax" housing 9 is adapted to be heated to approximately 1700° C. or even higher if desired, thereby causing the production of white heat to be discharged in blasts into the combustion chamber above the fuel bed. One of the particular advantages of constructing the body portion 9 of "carbofrax" which is a form of fused silicon carbide is its great heat retaining power. "Carbofrax" furthermore, does not deteriorate when subjected to high temperatures as do other materials when used under similar circumstances. It is common knowledge that when air is heated to approximately 450° C. that there is a tendency for the oxygen to become separated from the nitrogen, thereby permitting the liberated oxygen to enter the combustion chamber to cause complete combustion of the fuel bed from above. The "carbofrax" housing 9 appears to act on the superheated air to assist in causing liberation of the oxygen. The formation of oxygen flames heated to a white heat has been proven by repeated tests which also prove the substantially complete consumption of the fuel gases and volatile carbon products which tend to form smoke. The burning of the fuel from below and the intense burning of the fuel bed from above causes a substantially complete combustion to take place, resulting in a negligible production of smoke. The substantially complete combustion of the fuel due to the burning from above and from below obviates the production of clinkers in the fuel bed. This improved result permits any desired grade of fuel to be used in the fire box wherein the improved oxygenator is installed. The substantially complete combustion of the fuel together with the elimination of the production of clinkers results in the formation of a comparatively small quantity of ash, said ash being of a particularly fine powdered form containing very few large pieces of clinkers. It will thus be seen that the improved oxygenator being constructed of a particular carborundum product acts to produce improved results which heretofore have never been attained in earlier devices. The improved oxygenator having its intermediate or housing member formed of "carbofrax" has a tendency to not only superheat the entering air but also serves to cause liberation of the oxygen with a superheating of the same so that the superheated oxygen when entering the combustion chamber not only serves to produce a more complete

combustion of the fuel but also acts to consume the smoke forming products and at the same time reduce the quantity of ash 60 and eliminate the formation of clinkers.

The improved oxygenator may be put in position on a grate or removed from a grate by means of the eye 17 or any other suitable means connected with the retaining bolt 65 which serves to clamp the base and top members against the ends of the "carbofrax" housing.

I am aware that many changes may be made and numerous details of construction may be varied through a wide range without departing from the principles of this invention, and I therefore do not purpose limiting the patent granted hereon, otherwise than necessitated by the prior art. 70 75

I claim as my invention:

1. An oxygenator and smoke eliminator comprising an apertured base, an apertured top, a housing constructed of a carborundum product disposed between said base 80 and top, an apertured sleeve formed in said top and projecting downwardly into said housing and spaced therefrom, and means for clamping said base, top and housing together. 85

2. A portable oxygenator of the class described comprising a grooved base, a perforated top, a frustum shaped housing interfitting with said base and top, a sleeve in said top projecting downwardly into said housing, and means for holding said base, top and housing secured together to form a portable unit. 90

3. A portable oxygenator of the class described comprising an apertured and grooved base, an apertured top, a plain sectional housing interfitting with said top and base, retaining means for clamping said top and base against the ends of said sectional housing, and lifting means on the upper projecting end of said retaining means to facilitate movement of the oxygenator. 95 100

4. A combustion intensifier of the class described comprising apertured end members, a sectional housing disposed therebetween, means for clamping the end members against the ends of said sectional housing, said clamping means also serving as means to permit ready handling of the combustion intensifier. 105 110

In testimony whereof I have hereunto subscribed my name.

OLOF A. TOFFTEEN.
